SANITARY PHONE ATTACHMENT

Leon D. Levy, New York, N. Y.

Application June 22, 1944, Serial No. 541,625

1 Claim. (Cl. 179—185)

This invention relates to a sanitary attachment to the telephone and its main object is to provide a device easily attachable to any type hand "French" phone.

A further object of this invention is to provide an antiseptic holder at the mouthpiece of a telephone, and so arranged as not to interfere with the speaking voice, and yet provide ample disinfection to any possible germs, or neutralize any bad odors at the mouthpiece.

A further object of this invention is to provide a combination holder for an antiseptic solution and pencil at the mouthpiece of a telephone.

A further object of this invention is to provide an improved device of the above character, which is simple in construction, preferably made of one piece of metal or plastic material and which can be quickly and easily attached and detached from the mouthpiece of a telephone. The antiseptic holder can be refilled as desired and which can be manufactured at a low cost.

Various other objects and advantages of my invention will become apparent during the continuance of the following description.

In the drawing:

Figure 1 is a rear view of my device.

Figure 2 is a front view of my device.

Figure 3 is a plan view of my device.

Figure 4 is a bottom view of my device.

Figure 5 is a side view of my device.

Figure 6 is a view of my device as attached to a telephone mouthpiece.

Referring to the drawing, the numeral 10, is used to designate the mouthpiece of a hand or "French" type telephone, on said mouthpiece 10, there is attached a spring like clamp 11, having

flexible prongs 12, and 13, with end flaps 14, and center flap 15.

To the bottom of the clamp 11, there is attached or formed of the same material a band 16, which is widened at the end and formed into a loop 17, said loop is provided with perforations 18.

The loop 17, is also arranged to hold absorbent material 19, which is impregnated with an approved antiseptic solution.

10 The clamp 11, can be made to fit any type mouthpiece. The main feature is to arrange the antiseptic holder in close proximity to the mouthpiece.

The band 16, is curved sufficiently away from the clamp 11, so as to form a space for the insertion of a pencil or other object 25, the same being held against the clamp 11, by the resiliency of the band 16.

15 I have illustrated and described a preferred and satisfactory embodiment of my invention, but it will be understood that changes may be made therein within the spirit and scope thereof as defined in the appended claim.

I claim:

20 25 In an attachment to a telephone mouthpiece, a clamp resiliently attached to said mouthpiece, a holder for an antiseptic solution formed of a pliable material attached to the clamp and outwardly bent in a circular manner and the end 30 thereof bent back till it reaches the inner circular portion thus forming a container for material holding the antiseptic solution, said circular portion spaced sufficiently from said clamp so as to hold an object as a pencil.

LEON D. LEVY.
